UNITED STATES PATENT OFFICE.

GUSTAV SCHULTZ, OF NEW YORK, N. Y.

SHOE.

SPECIFICATION forming part of Letters Patent No. 449,500, dated March 31, 1891.

Application filed December 4, 1890. Serial No. 373,555. (No model.)

To all whom it may concern:

Be it known that I, GUSTAV SCHULTZ, of the city, county, and State of New York, have invented a new and Improved Shoe, of which 5 the following is a full, clear, and exact description.

The object of the invention is to provide a new and improved shoe, specially designed for use for weak-ankled feet, to permit the 10 wearer to properly sustain the weight of the body, so as to render walking easy and painless.

The invention consists in the particular construction and arrangement of parts, as hereinafter fully described, and pointed out in the 15 claim.

Reference is to be had to the accompanying drawings, forming a part of this specification, in which similar letters of reference indicate 20 corresponding parts in all the figures.

Figure 1 is a side elevation of the improvement with parts broken out. Fig. 2 is a perspective view of the sole and stiff plate; and Fig. 3 is a full-sized plan view of the sole, 25 showing in dotted lines the shape of the sole for a normal foot and also showing by dash and dot the extension on the inside of a weak ankle.

In weak ankles, as found in persons having 30 naturally-deformed feet or caused by spraining the foot, the instep is sunken or caved in, so as to project inwardly, as indicated by dots and dashes in Fig. 3. This outwardly-projecting portion of the foot, if pressed into an 35 ordinary shoe, soon begins to swell from the ankle upward, owing to the pressure on the afflicted part caused by the weight of the wearer, the center of gravity being outside the shoe-sole.

40 In my improved shoe the sole A is shaped essentially different from the soles for natural feet, the principal point being that the inner edge B is extended outward, while the outward edge extends farther inward, as can be 45 plainly seen by comparison of the sole A with the normal sole represented in dotted lines in Fig. 3. On the inner edge of the sole A, from about the heel part to the ball portion, is

erected a stiff plate or wall E, which preferably forms an extension of the heel-stiffener 50 F, forming part of the normal shoe and fastened in the heel part of the upper I. In order to conveniently fasten the heel-stiffening F and its extension E to the sole A, the lower part G of the said stiffener and its extension 55 is bent inward onto a corresponding part H on the top of the sole A and sewed thereon with the upper in the usual manner. The plate or wall E is curved downward from the heel toward the front, and is of sufficient, 60 height to press onto that portion of the deformed foot which extends over onto the inward edge of the sole A. The wall E thus tends to press the extended portion of the foot inward and downward, so that the weight 65 of the person is retained within the sole A, thereby permitting the party to walk easily, at the same time preventing any swelling of the foot.

As will be seen in Fig. 1, the upper I at the 70 instep is curved inwardly in an opposite direction from the normal upper, as the instep of a weak-ankled foot is the part which is sunken or caved in, as previously mentioned. The stiff plate or wall E permits the inward- 75 extending part of the deformed foot to have a free circulation of blood, so that swelling is not liable to take place. By a shoe constructed in this manner the party having weak-ankled feet in using the shoe can readily walk about without pain or swelling of the feet.

Having thus fully described my invention, I claim as new and desire to secure by Letters Patent—

80 A shoe having its sole extending outward at its inner edge beyond the line of a normal sole and provided with a heel-stiffener, the inside of which is extended forward to the ball portion and terminates thereat, substantially as described.

GUSTAV SCHULTZ.
